COOLER AND LUNCHEONETTE UNIT

Edgar Chester Harrison, Charles Town, W. Va., and Lynn E. La Garde and Marshall H. Lane, Atlanta, Ga., assignors to The Coca-Cola Company, Wilmington, Del., a corporation of Delaware

Application December 11, 1953, Serial No. 28,027

Term of patent 14 years

(Cl. D2—3)

To all whom it may concern:

Be it known that we, Edgar Chester Harrison, a citizen of the United States, residing at Charles Town, State of West Virginia; Lynn E. La Garde, a citizen of the United States, residing at Atlanta, State of Georgia; and Marshall H. Lane, a citizen of the United States, residing at Atlanta, State of Georgia, have invented a new, original, and ornamental Design for a Cooler and Luncheonette Unit, of which the following is a specification, reference being had to the accompanying drawings, forming a part thereof.

Fig. 1 is a front perspective view of a cooler and luncheonette unit embodying our new design; and

Fig. 2 is a similar view showing the rear thereof.

The side of our design not shown is a plain metal surface being like the side shown in the drawings with the grill omitted therefrom, however.

We claim:

The ornamental design for a cooler and luncheonette unit, as shown and described.
